STEAMING APPARATUS

John C. Crowley, Cleveland Heights, and
Adelbert E. Bronson, Shaker Heights, Ohio, as-
signors to The Dill Manufacturing Company,
Cleveland, Ohio, a corporation of Ohio

Application May 18, 1931. Serial No. 538,040

11 Claims. (Cl. 128—256)

This invention relates to a device which in its use is intended for giving a heat treatment, preferably by the use of steam, to the human scalp.

Specifically, the invention relates to a device which is portable and may be adjusted to various heights to suit the necessities of the occasion of its use, and the head-piece of the apparatus is further adjustable in a longitudinal direction to facilitate its use.

10 Further, the device provides an electrically operated device whereby heat is obtained by the use of an electric current to vaporize water or other fluid which is directed to the scalp of the person being treated through suitable passages in the apparatus.

Additionally, the apparatus provides a head-piece which is made of paper or other similar material which may be readily mounted upon and removed from the head-piece so that a new paper member may be used in connection with each treatment, thereby adding a sanitary feature to the apparatus.

Reference should be had to the accompanying drawing forming a part of this specification, in which:

Figure 1 is an elevation, with portions in section, showing the apparatus of the invention;

Fig. 2 is a front elevation;

Fig. 3 is a section upon the line 3—3 of Fig. 4;

30 Fig. 4 is a sectional elevation of a portion of the apparatus; and

Fig. 5 is an elevation of a hood used with the apparatus.

Referring to the drawing, 1 indicates a base member to which is secured an upright tubular portion 2. Within the tubular portion 2 there is a second tubular member 3 which telescopes with the tubular portion 2, and the member 3 is adapted to be raised and lowered in order to vary the height of the apparatus.

Secured to the tubular member 3 is a spring pressed latch 4, and mounted within the tubular member 3 but not movable therewith are two parallel members 5 and 6. The member 5 is stationarily mounted and is provided with a series of openings along its forward edge, as indicated at 5^a, these openings being adapted to receive the latch member 4, and when the latch member 4 is in engagement with one of the openings 5^a, it supports the tubular member 3 in its adjusted elevated position.

As before stated, the member 6 extends parallel with the member 5 and is provided with a plurality of snubbing projections 7 which are upon 55 the forward portion of the member 6 and in posi-

tion to engage with a portion of the latch 4 when it is desired to snub or push the latch 4 out of engagement with one of the depressions 5^a.

The member 6 has an extension 8 which at its lower end is articulated to a lever 9 which is pivoted at the point 10. This lever is provided with a foot engaging portion 11 so that when the foot engaging portion 11 is depressed it will cause the member 6 to be elevated and so snub the latch 4 out of engagement with the particular depression 5^a with which at the time it is in engagement.

Surrounding the extension 8 is a spring 12 which at one end abuts against a partition member 1^a of the base and its opposite ends abut against a collar 13 which is secured upon the extension 12.

At the upper end of the tubular member 3 there is a casing 14. This casing is hollow and is adapted to receive a removable container 15. This container at its upper end is provided with a lip 16 which engages with a flange 17 which is formed upon the inner wall of the container 15. Thus a support for the receptacle 15 is provided. The receptacle 15 has a re-entrant tubular portion 18 which is adapted to closely fit upon an electric element 19 which suitably supported in the housing 14. The electric element is by means of an electric cable 20 connected with a suitable source of electricity.

The container 15 at its upper end is provided with a pivoted bail 21 which bail has a loop portion 22 which is adapted to engage with a hooked member 23 that is supported upon a cover member 24. This cover member is provided with threads 90 upon a part of its exterior surface that are adapted to engage with threads formed on the outer end of the casing 14 so that when the cover 24 is screwed upon the casing 14 it becomes, in effect, attached thereto.

The cover 24 is provided with a handle which in the present instance comprises two arms 25 and 26 which are joined by a handle 27. By means of the handle 27, the cover 24 may be fastened upon or removed from the casing 14, and, furthermore, when the cover member 24 is secured upon the casing 14, the handle 26 serves as a means for lifting the whole apparatus and moving it from place to place.

Upon one side of the casing 14 there is secured an auxiliary handle 28 which may also be used in moving the apparatus from place to place.

At the upper end of the casing 14 there is a lateral tubular extension 29. This extension is adapted to receive the reduced neck 30 of a mem-

ber 31. The member 31 may be secured to the tubular extension 29 in any appropriate manner, as by means of a set screw 32. The member 31 supports a member 33 which at its rear portion 5 is provided with a dish-shaped part 34 which cooperates with the cylindrical portion 35 of the member 33. The portion 35 has an extending flange 36 which at the upper portion thereof is provided with a retaining member 37, and at its 10 lower portion is provided with a retaining member 38 which comprises a rod 39 having a stop member 40 at one end thereof against which abuts a spring 41, which spring surrounds the rod 39. The opposite end of the rod 39 extends through 15 an opening in the flange 36 and is provided with an elongated button 42. The button 42 is of such size that it cannot pass through the opening in the flange 35 through which the rod 39 extends.

A hood 43 is used in connection with the device 20 which has just been described, this hood being of the general form which is indicated in Fig. 1 of the drawing. The hood is preferably made of paper or some similar flexible material which is of small intrinsic value so that after once being 25 used it may be destroyed and a new one employed in connection with a subsequent use of the apparatus. Thus it is possible to use a new hood 43 in connection with each scalp treatment for which the apparatus is used.

The paper hood at its rear portion is cylindrical 30 and is attached at the upper portion of the member 35 by means of the retaining member 37. The hood at its lower portion is provided with a suitable opening through which the button member 42 extends and when the button member is turned one-half a revolution, it engages upon opposite sides of an opening in the hood so as to retain the hood in place.

The forward portion of the hood is shaped so as 40 to conveniently receive the head of the person to whom treatment is being applied, with the lower portion of the hood cut back, as indicated at 43^a, so as to fit against the back of the neck of the person being treated.

The portion 31, which was previously described, 45 is provided with a duct 31^a. At the upper end of the duct 31^a the member 31 is provided with a valve 44 which is mounted upon a shaft 45 which is better shown in Fig. 2. This shaft, at its outer 50 end, is provided with a handle 46. By operation of the handle 46, the valve member 44 may be moved to open or closed position, as well as to any desired intermediate position.

In using the apparatus, the handle 27 as well 55 as the handle 28 may be used in lifting and moving the apparatus to the place where it is desired for use. The cover 24 is removed, and the desired amount of liquid, such as water, is placed within the receptacle 15, after which the cover is replaced. By pressing upon the member 11 which, 60 as before described, is associated with the base 1, the latch member 4 is disengaged and therefore the hood and the parts associated therewith may be elevated to the desired extent, whereupon the member 11 is released, which permits the latch 4 to engage in an adjacent notch 5^a in the member 5, thus holding the hood at its proper elevated position.

If it is desired to give any lateral adjustment 70 to the hood, the same may be accomplished by releasing the set screw 32 and turning the member 30 and the parts carried thereby to any adjusted lateral position, after which the set screw 32 should be tightened.

With the apparatus thus adjusted, the electric

current is caused to pass to the heating element 19, which causes the heating of the water or other liquid in the receptacle 15, causing a mixture of steam and vapor to pass forwardly from the receptacle through the channel 31^a into the interior 80 of the head member 35 and to the interior of the hood 43, thus bringing the steam and vapor into contact with the scalp of the person being treated.

As has before been described, the portion 34 of the head member is concave, and by suitably 85 opening the valve 44, the steam and vapor coming from the receptacle 15 may be caused to pass into contact with the interior surface of the portion 34 which will cause the steam and vapor to be distributed uniformly throughout the hood and so come into contact with all portions of the scalp of the person receiving treatment.

Surrounding the casing 14 is a series of rods 47 the purpose of which is to form a guard so that the hand or hands of the person manipulating the apparatus may be kept from contact with the casing 14 which of course becomes quite hot 90 in the course of the use of the device when the heating element 19 is active.

The heating element 19 needs no specific description inasmuch as it specifically forms no part of the present invention, and this heating element may in its construction be of any suitable form of which there are many commercially 100 available.

In Fig. 5, the hood which is used with the apparatus is more particularly shown, and as before explained, it is suitably mounted upon the head 35, more particularly on the flange 36 carried by the head 35 so that it may be quickly attached and detached.

Preferably the hood is made of a piece of paper in one piece which may be rolled into cylindrical shape with the free edges overlapping, as indicated at 48 in Fig. 5. These free edges are provided with a buttonhole opening 49 which openings are adapted to slip over the button 42 which is shown in Fig. 1. When the openings 49 are slipped over the button 42, the button may be turned as indicated in Fig. 5 so as to extend transversely of the openings 49. As before explained, the hood is provided with an opening at the upper part thereof so that it may be engaged by the retaining member 36.

The sanitary features in connection with a 125 hood such as described have been heretofore referred to in the specification.

Obviously many specific changes and variations of the apparatus which is herein shown may be 130 made without departing from the spirit of the invention.

Having thus described our invention, we claim:

1. In apparatus of the character described, the combination of a standard, a housing supported upon the standard, a head member, a hollow conduit adjustably supporting the head member upon the housing and communicating with the housing and said member, said head member being provided with a convexed rear portion which acts as a steam deflector, and a 135 hood member detachably secured upon the head member.

2. In apparatus of the character described, the combination of a standard, a housing supported 140 on said standard, a head member, a hollow conduit supporting the head member upon the housing and communicating with the housing and said member, said head member being provided with a flange, a hood having a portion which is 145

- wrapped around said flange, and retaining means carried by the flange and engaging the hood. 45
3. In apparatus of the character described, the combination of a standard, a housing mounted upon said standard, a head member, a hollow conduit supporting the head member from the housing and communicating with the housing and said member, said head member being provided with a flange, a hood member made of flexible material, said hood member being adapted to be wrapped around said flange and said hood having overlapping end pieces, and a retaining member carried by the flange and engaging the overlapping ends of the hood. 50
- 10 4. In apparatus of the character described, the combination of a standard, a housing mounted upon the standard, a head member, a hollow conduit supporting said head member from the housing and communicating with the housing and said member, said head member being provided with a convexed rear portion the interior surface of which acts as a steam deflector, said hood also being provided with a flange, a flexible hood having a part thereof wrapped around the said flange, 25 and retaining means carried by the flange and engaging the hood. 55
5. In apparatus of the character described, the combination of a standard, a housing mounted upon the standard, a cover closing one end of the housing, a receptacle within the housing, and means connecting the receptacle with the cover whereby when the cover is removed the receptacle is removed with it. 60
- 30 6. In apparatus of the character described, the combination of a standard, a housing carried by the standard, a cover for closing one end of the housing, a handle associated with the cover, a head member supported by the housing, and a hollow conduit supporting the head member upon the housing and communicating with the housing and said member. 65
7. In apparatus of the character described, the combination of a standard, a housing supported upon the standard, a cover for closing one end of said housing, a handle carried by the cover, a receptacle within the housing, and means connecting the receptacle with the cover whereby when the cover is removed the receptacle is carried with it. 80
8. In apparatus of the character described, the combination of a standard, a cover closing one end of said housing, a handle carried by said cover, a second member associated with the housing, a head member, and a hollow conduit supporting the head member upon the housing and communicating with the housing and said member. 85
9. In apparatus of the character described, the combination of an adjustable standard, a housing carried by the standard, a cover member for one end of the housing, a handle associated with the cover, a head member, and a hollow conduit supporting the head member upon the housing and communicating with the housing and said member. 90
10. In apparatus of the character described, the combination of a standard, a housing mounted upon the standard, an electric heating element supported within the housing, a receptacle supported within the housing and having a reentrant portion which telescopes with the heating element, a cover associated with an open end of the housing, means for connecting the cover with the receptacle, a head member, and a hollow conduit supporting the head member from the housing. 105
11. In apparatus of the character described, the combination of a standard, a housing supported on said standard, a guard means mounted upon the housing and spaced therefrom, a head member, and a hollow conduit supporting the head member upon the housing and communicating with the housing and said member. 110
